UNITED STATES PATENT OFFICE.

PATRICK TRACY JACKSON, JR., OF CAMBRIDGE, MASSACHUSETTS, ASSIGNOR TO PAPER PRODUCTS MACHINE COMPANY, OF BOSTON, MASSACHUSETTS, A CORPORATION OF MASSACHUSETTS.

REINFORCED PAPER.

1,335,058.

Specification of Letters Patent. Patented Mar. 30, 1920.

Application filed September 9, 1918. Serial No. 253,131.

To all whom it may concern:

Be it known that I, PATRICK TRACY JACKSON, Jr., a citizen of the United States, residing at Cambridge, county of Middlesex, 5 and State of Massachusetts, have invented an Improvement in Reinforced Paper, of which the following description, in connection with the accompanying drawings, is a specification, like characters on the drawings representing like parts.

The invention to be hereinafter described relates to reinforced paper fabrics adapted for use as a protecting cover or wrapper, or as an efficient material for making bags or other containers.

The paper fabric may be reinforced by filaments, in the present instance, in the form of unspun fibers in substantially their natural condition, and the preparation 20 thereof may be carried into effect by the usual process of scutching, hackling, drawing or any or all employed in the preparation of ramie, hemp, sisal, flax, and other forms of fiber wherein the staple or length 25 of the fiber is greater than in some of the other natural fibers. It is preferable to employ fibers of long staple, but it is to be understood that any natural fiber unspun or untwisted may be employed.

30 In Letters Patent, No. 1,255,818, granted to P. T. Jackson, Jr., February 6, 1918, is shown, described and claimed a paper fabric reinforced by unspun fibers such as described above. The present application relates to a paper fabric differing in certain respects from that shown in said patent, and a method of making the fabric.

In carrying the invention into practical effect, the fibers which have been previously prepared and arranged in substantially parallel relation in the usual fiber preparing machines, are fed longitudinally to a strip of paper or other suitable material, and preferably are adhesively secured there- 40 to. The paper strip may be previously gummed and then moistened to secure the fibers thereto, or an adhesive coating may be applied to the paper strip as it is fed through the machine. In some cases it may 45 be desirable to superpose upon the paper

strip, referred to, a second strip of paper or other suitable material, but this is not indispensable.

After the unspun fibers have been applied to the strip or between the strips, the present invention contemplates that the sheet thus formed shall be severed at intervals to form sections. Then these sections are applied to another strip of paper or other suitable material, which, in some instances, 55 may be reinforced by unspun fibers extending longitudinally thereof. An important feature of the invention consists in applying the sections to the strip so that the unspun fibers of the sections extend transversely to 60 the length of the strip, said sections being preferably secured to the strip by a waterproof or other appropriate adhesive. The sections may be superposed upon the strip in end to end relation, so that in effect the 65 strip may be reinforced by unspun fibers extending transversely thereof throughout the length of the strip.

By this method an efficient paper fabric may be readily and rapidly manufactured, 70 comprising a strip of paper having groups of transverse unspun fibers mounted on a backing, and so disposed with respect to the strip, as to supply efficient transverse reinforcement thereto, and where the unspun 75 fibers are also applied to the strip longitudinally thereof, an effective fabric is provided having reinforcing fibers extending both longitudinally and transversely of the strip. Also, the reinforcement had by these 80 fibers is desirably supplemented by the backing for the transverse fibers.

The character of the invention may be best understood by reference to the following description of a reinforced paper fabric 85 which may be made by a method conveniently practised in an apparatus shown in the accompanying drawings, wherein:—

Figure 1 is a vertical longitudinal section showing conventionally the elements of an 90 apparatus for making the sections or backings having the transverse unspun fibers applied thereto;

Fig. 2 is a vertical longitudinal section of the portion of an apparatus having elements 100

shown conventionally for applying unspun fibers to a strip of paper for receiving the sections or backings;

5 Fig. 3 is a plan of a strip of paper having the sections or backings applied thereto;

Fig. 4 is a plan of a reinforced paper fabric produced by the method;

10 Fig. 5 is a modified form of reinforced paper fabric which may be made by the method; and

Fig. 6 on a very large scale is a section taken on line 6—6 of Fig. 5.

15 The sections having the unspun fibers extending transversely thereof may be made by any suitable means. To accomplish this, in the present instance, an apparatus is shown in Fig. 1 of the drawing, comprising a pair of opposed calender rolls 1 and 3 which may be provided with any suitable 20 driving means unnecessary to illustrate herein. A strip 5 of paper or other suitable material may be led from a supply roll 7 past a guide roll 9 to and between said calender rolls. This strip of paper may have a waterproof or other suitable adhesive coating on one face thereof, which may be applied by passing the strip between a pair of upper and lower rolls 11, the lower roll being adapted to conduct the adhesive to the strip 30 from a trough 13.

35 The unspun fibers 14 may be delivered to the paper from a suitable station in general parallel relation. To accomplish this, an endless belt 15 may be provided for feeding the fibers over a table 16 to and between the calender rolls, and in the course of their transit therebetween, they are pressed to the adhesively coated paper strip and secured thereto.

40 In some instances it may be desirable to superpose a strip of thin paper or other suitable material upon the fibers. To accomplish this a strip 17 of paper or other suitable material may be led from a supply roll 19 over a guide roll 21, and thence to and between calender rolls, which will press the superposed strip on the fibers and into adhesive engagement with the coating on the lower strip.

50 The present invention contemplates that the material thus reinforced shall be cut at intervals into sections. This may be accomplished by any suitable means, which, in the present instance, may be in the form of a cutting roll 23 provided with a knife 25 cooperating with a hard surfaced roll 26 driven by any suitable driving means unnecessary to be illustrated herein. The material may be conducted over a table 27 past the cutter roll, and in the course of its transit, will be severed into sections 29. These sections may be fed by a pair of rolls 31 beyond one end of the table, where the

sections may be stacked on a suitable support 33.

Any suitable means may be provided for preparing the strip of paper or other suitable material to receive the sections produced as described. To accomplish this, in the present instance, a pair of calender rolls 35 and 37 (Fig. 2) are provided driven by any suitable means. A strip of paper 39 or other suitable material may be led from a supply roll 41 past a guide roll 43 to and between the calender rolls.

If unspun fibers 53 are to be applied to the paper strip 39, they may be conducted from a suitable station by an endless belt 54 working over a table 55 to and between the calender rolls 35 and 37, which will serve to press the fibers to the adhesive coating on said paper strip.

Suitable means may be provided for applying a waterproof or other appropriate adhesive coating to the paper strip 39. To accomplish this, the latter may be fed between a pair of upper and lower rolls 57, the lower of which conducts the adhesive from a trough 59 to the lower face of the paper strip. The unspun fibers are pressed and secured by the calender rolls to the adhesive coating on the strip.

Then the sections 29 may be transferred manually or by suitable mechanism from the stack support 33 to the paper strip 39. The sections may be conveniently applied to the paper strip as it is fed between the calender rolls 35 and 37. For this purpose an endless belt 60 may be provided having a horizontal run 60° and an inclined run 60° above the belt 54 and leading to the bight between the calender rolls, the latter serving to press the sections onto the adhesive coating on the paper strip. The sections are placed on the strip progressively in end to end relation, and the ends of adjacent sections may meet or may have slight spaces between them as desired.

It will be understood that the sections may be variously applied to the longitudinal strip 39. If each section comprises merely a backing with fibers thereon, the section may be superposed on the strip, so that the fibers of the section will contact with the strip or with the longitudinal fibers thereon, so that the product will comprise outer paper layers 53 and 55 with longitudinal fibers 57 and transverse fibers 59 between said layers and embedded in an adhesive layer 61, as will be noted in Fig. 4.

If, however, each section has a covering strip 17 of paper or other suitable material, the product will comprise a paper layer 63, longitudinal fibers 65, and transverse fibers 67 between paper layers 69 and 71, the fibers 65 being embedded in an adhesive layer 73,

and the fibers 67 being embedded in an adhesive layer 75, as will be noted in Fig. 5. Since the covering strip is preferably a thin tissue, it preferably will be interposed between the stronger outer paper layers 63 and 71.

It will be understood that the invention is not limited to the specific articles and method described herein, but that various deviations may be made therefrom without departing from the spirit and scope of the appended claims.

What is claimed is:

1. As an article of manufacture, a reinforced fabric comprising a paper layer having strengthening unspun fibers secured thereto extending in general parallel relation longitudinally of the paper layer, and paper sections having strengthening unspun fibers secured thereto extending in general parallel relation transversely to the paper layer, said paper sections and their fibers being each adhesively secured as a unit to said paper layer.
2. As an article of manufacture, a paper fabric comprising in its construction a layer or strip of paper having reinforcing filaments secured thereto in general parallel relation longitudinally of the paper layer or strip, and paper sections having reinforcing filaments secured thereto and extending in general parallel relation, and an adhesive

uniting the reinforced paper sections to the paper layer or strip with the reinforcing filaments of the paper sections extending 35 transversely of the paper layer or strip.

3. As an article of manufacture, a reinforced fabric comprising a paper strip, paper sections secured to said strip in end-to-end relation, and strengthening unspun 40 fibers secured to said sections and extending transversely to said strip.

4. As an article of manufacture, a reinforced fabric comprising a paper strip, paper sections secured to the paper strip, and 45 reinforcing filaments secured to said sections and extending transversely to the paper strip.

5. As an article of manufacture, a reinforced fabric comprising a paper layer having 50 strengthening filaments extending longitudinally thereof, paper sections having strengthening filaments secured thereto, said paper sections being superposed on the paper layer with the strengthening filaments of said sections opposed to and extending transversely to the strengthening filaments of said paper layer, and a waterproof adhesive for securing said fibers to said paper layer and sections. 60

In testimony whereof, I have signed my name to this specification.

PATRICK TRACY JACKSON, JR.
